Application April 3, 1937, Serial No. 134,911

11 Claims. (Cl. 141—9)

This invention relates to new and useful improvements in apparatus for washing, rinsing, and drying dishes, silverware, and the like.

The primary object of the invention is to provide apparatus for efficiently and scientifically projecting suitable fluids against the surfaces of dishes, silverware, and the like for washing, rinsing, and drying the same.

A further important object of the invention is to provide mechanism adapted for projecting at considerable velocity, throughout substantially the entire interior of a closed compartment, a finely atomized washing fluid which will be caused to impinge against the surfaces of dishes, and the like, with sufficient force and at a proper angle to completely cleanse the same.

Still another object of the invention is to provide a single liquid impelling unit which is so constructed and arranged that all points throughout the interior of a compartment in which dishes, or the like, may be arranged will fall within the effective treatment area of the impelled fluid and will be uniformly subjected to the action thereof.

A still further purpose of the invention is to provide dish and silverware supporting means which will position said objects relative to fluid impelling means in such a manner that the various surfaces of the different, conventionally-shaped objects will be properly arranged for efficiently subjecting the same to treatment by the fluid.

Other objects and advantages of the invention will be apparent during the course of the following description.

In the accompanying drawings forming a part of this specification and in which like numerals are employed to designate like parts throughout the same:

Figure 1 is a perspective view of the dish and silverware washing, rinsing, and drying apparatus embodying this invention;

Figure 2 is a top plan view of the machine disclosed in Figure 1 with the cover removed;

Figure 3 is a longitudinal sectional view taken on line 3—3 of Figure 2;

Figure 4 is a transverse sectional view taken on line 4—4 of Figure 2;

Figure 5 is a transverse sectional view illustrating the action of the impeller device in projecting fluid at a high velocity and in a finely atomized condition so that all portions of the interior of the compartment or housing will fall within the effective range of the impelled fluid;

Figure 6 is a detail horizontal sectional view taken on line 6—6 of Figure 4;

Figure 7 is a detail vertical sectional view taken on line 7—7 of Figure 6; and

Figure 8 is a detail perspective view of a cup supporting tray or shelf which forms a part of the dish and silverware supporting rack, disclosed in detail in Figures 2, 3, and 4.

In the drawings, wherein for the purpose of illustration is shown the preferred embodiment of this invention, the reference character 10 designates in its entirety the main body portion of the washing machine housing. This main body portion is open at its top and is closed by the removable cover 11.

Referring particularly to the main body portion 10 of the housing, the bottom wall of the same is formed by an aluminum casting 12 having an upstanding marginal flange 13. Extending longitudinally of the bottom 12 is a shallow trough 14 which is adapted to cooperate with an impeller unit in a manner to be described at a later point. At the junction between one longitudinal edge of the trough 14 and the adjacent flat bottom wall, an upstanding longitudinally extending flange 15 is provided. Figures 3 and 6 disclose this flange 15 as terminating at its opposite ends short of the marginal flange portions 13 which are located at the opposite ends of the aluminum casting 12. The terminating of the ends of the upstanding flange 15 short of the ends of the bottom casting provides openings 16 at the opposite ends of the trough which establish communication between the trough and the side of the bottom casting lying laterally of the upstanding flange 15. Figure 4 clearly illustrates the fact that the remaining side of the bottom casting 12 has unobstructed communication with the trough 14.

The upstanding flange 15 functions to maintain a proper relationship between the impeller and deflector blades to effect efficient fluid dispersion; to prevent fluid from flowing on or against the movable impeller blades and thereby interfering with the action of said blades to effect proper fluid dispersion; and to limit the return flow of the fluid which has accumulated in the bottom of the housing to the left of the flange 15 (see Figures 4 and 5) to the trough for reuse at the end portions only of the latter.

At the opposite ends of the bottom casting 12, integral upstanding extensions 17 are formed on the casting. These extensions 17 carry bearing bosses 18 in which is journaled the impeller shaft, to be described at a later point. Figures 3, 6, and 55

7 disclose a drain opening 18 at one end of the trough 14. This drain opening is normally closed by a hinged cover 20 which is sealed against the outer surface of the casting by means of the packing or gasket ring 21. A suitable latch 22 is provided for clamping the cover 20 against the end surface of the housing wall to prevent leakage of liquid through the drain opening 19. It will be appreciated that with the cover 20 unlatched and raised, the entire interior of the housing may be flushed out and drained for the purpose of removing any foreign matter which has accumulated within the housing.

At the four corners of the bottom casting 12, legs 23 are provided for supporting the housing in an elevated position to allow clearance for the trough 14 and an electric motor which will be described at a later point as being mounted at one end of the housing.

20 The side walls of the main body of the housing 10 are formed of sheet material 24 of suitable gauge and exterior finish. Suitably attached to the side wall 24, at one end of the housing, is a connection 25 by means of which suitable cleaning and rinsing fluid may be admitted to the interior of the housing. The same end wall of the housing is provided with an overflow cock 26 which is located on the opposite side of the trough 14 from the location of the inlet connection 25. 30 The position of the overflow outlet 26 is very important for it is to be arranged at an elevation which will prevent filling of the housing with a cleaning or rinsing fluid to a level above that shown in Fig. 4 which would submerge the impeller shaft, to be described at a later point. The position of the inlet 25 is optional although it preferably should be arranged at a higher level than the overflow outlet 26. This inlet connection 25 should be of such construction that a hose, 40 or the like, may be attached thereto at one end and connected to a hot water spigot at its other end. The overflow outlet determines the charging level for the fluid when the impeller unit is not in operation. This level drops when the impeller unit is operating, due to the volume of the fluid which is in motion within the housing and the operating level is shown in Fig. 5.

Figure 4 discloses the cover 11 as having a channel 27 formed at its marginal edge. A suitable packing gasket 28 should be cemented or otherwise secured within the channel 27. By positioning the cover 11 with the channel 27 and gasket 28 receiving the upper edge of the side wall 24 of the bottom of the housing, a seal will be effected between the top and bottom portions of the housing. By inspecting Figures 1, 4, and 5, it will be seen that the cover 11 is formed with a top wall 29 so shaped to most efficiently cooperate with the dishes, and the like, which are to be arranged within the housing. A suitable handle 30 is mounted on the top wall 29 of the cover for facilitating removal of the latter from the main body 10 of the housing.

65 The mechanism disclosed for impelling a finely atomized fluid at high velocity in such a manner that the fluid particles will be forcefully delivered against the surfaces of dishes, and the like, arranged in different portions of the housing, has been developed as a result of much experimental work. It has been determined that many dimensions are critical. The particular shape and arrangement of the various elements of the impeller unit also have been found to be extremely important. The essential features of construc-

tion and mode of operation of this impeller mechanism will now be described.

Extending longitudinally of the trough 14 is an impeller shaft 31 which has its opposite end portions journaled in the bearing bosses 18. Figure 6 discloses the extremity 31a of the impeller shaft as projecting outwardly of the housing for connection with the electric motor 32 which is disclosed in Figures 1, 2, and 3. This electric motor 32 is suitably fastened to the shelf portion 10 33 of a bracket which is provided with the mounting lugs 34, adapted to be suitably secured to the bottom of the casting 12 in the manner best illustrated in Figure 4. An upstanding flange 35 also is provided on the motor mounting bracket 15 and engages the outer end wall of the housing, as best shown in Figures 1 and 3.

Figures 4 and 6 illustrate the impeller shaft 31 as being positioned off-center with respect to the trough 14. In other words, the axis of the impeller shaft 31 is located closer to the edge of the trough 14 which is provided with the upstanding flange 15. A series of impeller wheels 36 are mounted on the impeller shaft 31 with their hub portions properly keyed to the shaft. The spacing 25 of these impeller wheels is considered to be very important. It has been determined that they must be spaced from approximately $\frac{1}{2}$ of an inch to approximately $1\frac{1}{2}$ inches from each other and that the best results are obtained when they are spaced approximately 1 inch apart, i. e., with impellers approximately 3 inches in diameter and rotating about 3500 revolution per minute. With this size impeller rotating at about the designated speed, the peripheral speed of the impeller will be approximately 2750 feet per minute. Figure 4 illustrates one of these impeller wheels. It is to be understood that all of the impeller wheels are of like construction. The impeller disclosed in Figure 4 is formed with four blades 37 which are curved longitudinally. The shaft with these impeller wheels is to be rotated in a clockwise direction, as viewed in Figure 4. The impeller shaft should be mounted so that the extremities of the blades 37 clear the inner bottom surface of the trough 14 by approximately $\frac{1}{8}$ to $\frac{1}{4}$ of an inch. The extremities of the blades 37 should clear the inner surface of the upstanding flange 15 by approximately $\frac{1}{16}$ of an inch. These dimensions have been found to be critical.

Arranged between each adjacent pair of impeller wheels 36 is a fixed deflector blade 38. By an inspection of Figure 4, it will be seen that each of these deflector blades is formed with a horizontally arranged shelf portion 39 at the inlet side of the trough. From the horizontal shelf 39, the blade is curved downwardly and upwardly at 40 to terminate in an upstanding, inwardly curved, end portion 50. Figure 4 discloses the fact that the curved portion 40 of each deflector blade is not concentrically arranged with respect to the trough 14. This curved portion 40 also is eccentrically arranged with respect to the axis of the impeller shaft 31. The curved portion 40 of each deflector blade 38 is spaced above the bottom wall of the trough approximately $\frac{1}{2}$ an inch at the vertical center of the impeller wheels 36. The impeller blades 37, therefore, dip down beneath the curved portions 40 of the fixed deflector blades. At the 70 sides where the blades enter and leave the spaces between the fixed deflectors 38, the extremities of the impeller blades 37 approximately register with the fixed deflectors. That is, the extremities of the impeller blades 37 do not project be- 75

yond the fixed deflector blades 38 at the points where the impeller blades enter and leave the spaces between the fixed deflectors.

In Figures 4, 6, and 7, the outer ends of the horizontal shelf portions 39 of the fixed deflector blades are illustrated as being countersunk in the surface of the casting, as illustrated at 51. This countersinking of the deflector blades arranges their top surfaces flush with the top surface of the bottom wall casting 12. Figures 4 and 6 disclose the upstanding flange 15 at the discharge side of the trough as being provided with notches or countersunk portions 52 which receive the curved portions of the deflector blades 38 to assist in supporting and maintaining these blades in fixed positions with respect to the impeller blades 37. It will be understood that the fixed deflector blades 38 are suitably secured in their positions at points 51 and 52.

20 The action of the impeller blades 37 and deflector blades 38 in projecting the fluid placed in the housing has been observed under strong light rays through transparent walls of an experimental housing. The action of the impeller mechanism will be described as follows:

Figure 4 illustrates the fact that a very low level of liquid is maintained in the housing. As an indication of the extremely small amount of water required to permit efficient operation 30 of this impelling mechanism, the bottom of the housing measures approximately 20 inches in length and 16 inches in width. The height of the housing, including the cover, is approximately 16 inches. A housing of this size, with 35 the rack illustrated for supporting the dishes, will receive the normal amount of dishes for a family of five or six. Only about one gallon of fluid is needed in a housing of this size. The motor 32, employed for driving the impeller shaft 31, should be of a high speed type. It has been determined that motor speeds ranging from 1,750 to 3,500 R. P. M. are satisfactory. The most efficient speed has been determined to be from 3,000 to 3,500 revolutions per minute. With 40 the low liquid level maintained and the high rate of rotation of the impeller shaft, it will be appreciated that the fluid will be projected at a high velocity and in a very finely atomized condition. This action distinguishes materially from 45 a fluid splashing action which is employed in practically all forms of dish-washing machines now on the market.

Figure 5 illustrates the action of the impeller mechanism for projecting the fluid. It has been determined that the impeller blades 37 will deliver fluid through but little more than half the interior of the housing. The range of delivery of fluid by the impeller blades 37 is illustrated in Figure 5 as extending from the point 53 on the adjacent side wall 24 of the housing to the point 54 on the top or cover of the housing. This point 54 is located slightly beyond a vertical plane extending through the axis of the impeller shaft 31. It will be seen that the water, or other fluid, projected by the impeller blades 37 will travel approximately in straight lines which are tangential of the path of travel of the impeller blades 37.

By extensive experimental work, it has been 70 found that the fixed deflector blades 38 will cooperate with the movable impeller blades 37 for effecting a delivery of fluid from the point 54 to approximately the point 55 which is located at the bottom wall of the housing just to the right of the intake side of the trough 14. The

arrow lines, employed for indicating the movement of fluid between the points 54 and 55, are intended to illustrate the fact that the water projected by the fixed deflector blades 38 travels through curved paths. This movement of the water, or other fluid, is not produced as a result of the pull of gravity. The fluid discharged from the fixed deflector blades 38 travels with approximately the same velocity and is atomized to approximately the same extent as the water 10 actually projected from the ends of the impeller blades 37. It will be noted that the upwardly curved end portion 50 of the deflector blades 38 is pointed substantially at the point 54. This curvature or angle of projection of deflector portion 50 is very important for it causes the water projected from the fixed defectors 38 to start its range of action at approximately the point where the range of action of the impeller blades 37 stops.

It is, of course, very apparent that the impeller blades 37 dip fluid from the trough 14 and project the fluid tangentially outwardly between the points 53 and 54. As the water, or other fluid, is expelled from the trough 14 by the impeller blades 37, more water flows into the trough from the bottom of the housing on both sides of the trough. The water from the right-hand side of the housing body is permitted to flow into the trough throughout the length of the latter. 30 The fluid from the left-hand side of the housing bottom is permitted to enter the trough at the ends of the latter or through the portions 16 where the upstanding flange 15 has been omitted. It is very obvious that the high speed of 35 rotation of the impeller blades 37 will create a low pressure or suction zone during their travel from the point where the fluid is expelled from the same to the point where they are again supplied with fluid. This low pressure area or zone materially influences the movement of fluid occupying the space between the points 54 and 55 and causes the fluid discharged from the fixed deflector blades 38 to travel in the arcuate paths indicated. This low pressure or suction produced by the movable impeller blades 37 also causes the fluid in the bottom of the housing and positioned to the right of the trough 14, as viewed in Figure 5, to be sucked into the trough. Of course, the level of the fluid on both sides of the trough 14 is materially lowered while the impeller unit is 50 in operation. This is due to the fact that a large quantity of fluid is being dispersed throughout the interior of the housing. It has been observed that during rotation of the impeller blades, only 55 a comparatively shallow film of water, or other fluid, is maintained on the bottom of the trough 14.

It would appear that the water delivered by the fixed deflector blades 38 reaches the blades 60 as a result of the action of the impeller blades 37 in creating low pressure areas between the paths of rotation of the impeller blades or in the zones occupied by the fixed deflector blades. These low pressure areas will cause water to be 65 sucked from the bottom of the housing at the right of the trough. This water is caused to travel longitudinally of the shelf portion 39 of each deflector blade and then longitudinally of the curved portions 40 and 50 to be expelled 70 from the extremities of the upstanding curved portions 50. It has also been determined that water, or other fluid, is delivered to the curved portions 40 of the deflector blades 38 as a result of axial movement of water from the impeller 75

blades 37 to the spaces between adjacent pairs of impeller wheels. This axial movement of water from the blades 37 is known as "side slip" and is a well recognized principle of aero- and hydro-dynamics.

A rack structure for supporting dishes, silverware, and the like has been scientifically designed to take full advantage of the particular paths of movement of fluid in the two sides or portions of the housing which receive the fluid from the impeller blades 37 and the deflector blades 38. This rack structure will be described as follows:

Figures 2, 3, and 4 clearly illustrate the bottom of the rack as consisting of a single wire strand 56 which is shaped in plan to correspond with the horizontal sectional shape of the bottom casting 12 and is of proper length and width to nicely fit within said casting. The end portions of this base or bottom strand of the rack are curved or bowed upwardly at 57 to clear the end projections 17 formed on the bottom casting 12 for supporting the bearing bosses 18.

A suitable number of strands of wire 58 is provided for permitting spacing of the same approximately 3 inches apart throughout the entire length of the rack. These strands of wire 58 are properly bent to form dish receiving troughs 59 which are arranged in parallelism with respect to each other and are inclined outwardly or laterally with respect to the perpendicular. This angular arrangement of the troughs 59 results in supporting the type of dish indicated at 60 at a proper angle to cause all surfaces of the same to fall within the effective treatment range of the fluid expelled by the impeller blades 37. The lower ends of all of the strands of wire 58 are suitably welded or brazed to the bottom or base strand 56 at the points 61. A suitable number of longitudinally extending bracing strands 62 are provided for maintaining the various strands 58 in proper parallelism with respect to each other. The upper ends of all of the strands 58 are interconnected by one of the bracing strands 62, as best illustrated in Figures 2, 3 and 4. Extending between each end portion of the base strand 56 and its overlying strand 58 is an upstanding brace arm 63 which reinforces the various strands 58 which form the dish receiving troughs 59.

At the opposite side of the housing, the rack consists of a suitable number of wire strands 64 arranged in parallelism and spaced approximately 3 inches apart, which strands are properly shaped to form the stepped bowl supporting shelves 65. These strands 64 are connected at their bottom ends to the base or bottom forming strand 56 of the rack, as at 66. The various strands 64 are reinforced and braced by a suitable number of longitudinally extending strands 67. The upper extremities of all of the strands 64 are interconnected by an arched strand 67a, supported in a manner to be described at a later point, as best illustrated in Figures 2, 3, 4, and 8.

The end strands for the bowl shelves 65 are of different construction than the remaining or intermediate strands 64 and are best illustrated in Figures 4 to 8. Starting from each end of the base strand 56, a strand 69 extends upwardly to the bend 69a and then downwardly in the two angularly arranged portions 80 and 80a. From the bottom of the portion 80a, the strand extends laterally in the plane of the inner shelf 65 and is welded or brazed at its extremity 80b to the vertical portion of strand 69. The outer

shelf portion is formed by a strand 64a which follows the contour of the strands 64 up to the strand 69 to which it is brazed or welded, as at 64b. The reinforcing and bracing strands 67 tie the end forming strands to the intermediate strands 64 in the manner best illustrated in Figure 8. The ends of the arched strands 67a are brazed or welded to the angles formed by the portions 80 and 80a, as at 67b.

It will be noted by inspecting Figure 4 that the bowls 68 are supported in stepped relation transversely of the housing by the shelves 65. The inner shelf is located lower than the outer shelf. These shelves are inclined transversely of the rack so that they will support the bowls 68 in a manner to cause them to lean laterally outwardly or so that the planes of their mouths will be inclined outwardly. The inclination, however, should not be so extreme as to result in lateral tipping of bowls of average or ordinary shape. This manner of supporting the bowls 68 is such that the fluid discharged from the fixed deflector blades 38 and traveling through curved paths will effectively treat all surfaces of the bowls.

A series of relatively closely spaced, parallel, wire strands 70 extend between and are suitably brazed or welded to the longitudinal strands 62 and 67 which are secured to the strands 58 and 64, respectively, just inwardly of the upper extremities of these last mentioned strands. The location of these strands 70 is clearly illustrated in Figures 2, 3, and 4. These strands 70 collectively form a shelf for glasses. This shelf slopes laterally for the purpose of causing water to drain from the depressions 71 usually provided in the bottoms of the glasses 72. The glasses should be placed upon the shelf formed by the strands 70 in an inverted condition so that the water expelled from the impeller blades 37 will readily reach the interior of the glasses.

Positioned above the lower bowl supporting shelf 65 is a cup receiving shelf 74 which is formed by a plurality of strands 75. Each one of these strands 75 is bent around the arched strand 67a to form a hinge 76 for the cup shelf. The various cup shelf strands are interconnected and braced by the longitudinally extending strands 77, 78, and 79. The strand 79 is suitably connected to the outer ends of all of the parallel strands 75. The longitudinal strand 78 engages at its opposite ends the bends 69a which function as supports for the hinged shelf 74 to locate the latter in its operative position. It will be noted that this operative position of the shelf 74 will support cups 81 so that water will be drained from any depressions formed in the bottoms of the cups. It is necessary to hinge this cup supporting shelf 74 so that it may be thrown into an inoperative position, above the glass supporting shelf 70, to permit bowls 68 to be removed from and placed on the inner bowl receiving shelf 65. By comparing the disclosures of Figures 4 and 5, it will be appreciated that the cups 81 are positioned so that they will receive water from both the impeller blades 37 and the fixed deflector blades 38. In other words, the cups 81 are located approximately at the point 54.

Intermediate the ends of the glass shelf, a wire mesh basket 82 is secured. This basket is intended to receive silverware and is so shaped that it tapers downwardly. This tapering of the silverware basket will permit the outer ends of silverware placed therein to spread or fall apart for causing the treatment fluid to more easily 75

and effectively reach all of the surfaces of the said silverware.

The mode of operation of this dish and silverware washing, rinsing, and drying machine will 5 now be described in detail.

The dish and silverware supporting rack is, of course, separately made so that it may be removed from the housing to facilitate cleaning the interior of the housing and the rack. After 10 the rack is placed within the housing and the dishes and silverware to be cleaned are placed within and upon the proper troughs and shelves, respectively, water of suitable temperature may be supplied to the compartment or interior of the 15 housing through the inlet connection 25. During feeding of water to the housing, the outlet or overflow spigot 26 should be left open. The feeding of hot water to the housing should continue until it starts running out of the overflow 26. 20 The feeding of water then should be stopped and the overflow 26 closed. A suitable amount of soap powder, or the like, should then be placed in the water positioned within the housing. After supplying the soap powder, the cover 11 should be 25 positioned and the electric motor 32 started. A suitable cleansing fluid will be created quickly within the housing by the churning of the water due to the action of the rotating impeller wheels.

With the housing properly charged with the 30 dishes and silverware to be cleaned and the cleansing fluid, operation of the motor for a very short period of time, approximately one or two minutes, will be sufficient to thoroughly cleanse all of the dishes and silverware. Due to the high 35 velocity at which the cleansing fluid is forcefully projected against the surfaces of the dishes and silverware, the way the fluid is directed, and the manner in which the dishes are supported in relation to the fluid paths, the various objects 40 will be thoroughly cleansed of all edible substances left thereon. During demonstrations of this machine, it has been determined that food substances, such as egg yolks, stewed tomatoes, dried milk film, and the like, even if left to harden for two or three days, will be quickly and completely removed from the surfaces of the dishes 45 and silverware when subjected to the action of the water dispersed by the impelling mechanism of this machine.

After the objects have been properly cleaned, the trap door 20 should be opened for completely draining the washing fluid and food particles from the interior of the housing. After the housing is thoroughly drained, the trap door 20 should 50 be closed and properly latched. Clean rinsing fluid should then be supplied to the interior of the housing through the inlet 25. The overflow spigot 26 should be employed for accurately determining the height to which the rinsing fluid is 55 permitted to rise. After a proper amount of rinsing fluid, such as hot water, is supplied to the housing, the impeller mechanism should again be operated for a very short period of time. The dishes and silverware will be thoroughly rinsed 60 when subjected to the rinsing fluid which, of course, will be projected throughout the entire interior of the housing in the same manner as that described above in connection with the cleansing or washing fluid.

It may be found desirable to accomplish rinsing 70 with a continuous flow of rinsing fluid. For such a continuous rinse, the fluid is permitted to enter the inlet 25 while the impellers are rotating, and the excess fluid will be discharged through the 75 overflow spigot 26 which is left open for that

purpose. Since the rinsing process requires but a few seconds, there will be required but a relatively small amount of additional fluid for each continuous rinse. After the dishes and silverware are thoroughly rinsed, the rinse water may 5 be drained from the housing by means of the trap door 20.

With all of the rinse water removed from the housing, the impeller unit may be operated for a short period of time to thoroughly dry the dishes 10 and silverware. The impeller mechanism will create a circulation of air throughout the interior of the housing which will effect this drying. It has been determined by observation of the machine during a drying operation that 15 the drying air is impelled or projected in the same manner as the washing and rinsing fluid.

It is to be understood that the form of this invention herewith shown and described is to be taken as a preferred example of the same and 20 that various changes in the shape, size, and arrangement of parts may be resorted to without departing from the spirit of the invention or scope of the subjoined claims.

Having thus described the invention, I claim: 25

1. A dish and silverware washing, rinsing, and drying machine comprising a housing having a shallow trough in the bottom wall thereof, an impeller shaft journaled in the housing above said trough, a series of axially spaced impeller wheels 30 having longitudinally curved blades fixed to said shaft, the blades being of proper length to dip into said trough, a fixed deflector blade extending transversely of the trough between each adjacent pair of impeller wheels and terminating in an 35 upwardly curved end portion at the discharge side of the impeller wheels, means for supplying the housing with a treatment fluid to a level below the impeller shaft, and means for rotating said impeller wheels at high speed to cause fluid from 40 the bottom of the housing to be expelled at high velocity and in a finely atomized condition from the ends of the impeller blades and the upwardly curved ends of the deflector blades.

2. A dish and silverware washing, rinsing, and 45 drying machine comprising a housing having a shallow trough in the bottom wall thereof, rotatable means including a plurality of axially spaced blades arranged to dip into the trough for impelling fluid from said trough at a high velocity 50 and in a finely atomized condition throughout a portion of the interior of said housing extending from the discharge side of the trough, and fixed deflector means extending between adjacent blades and so shaped as to cooperate with the 55 rotatable means for directing fluid from the trough at high velocity and in a finely atomized condition throughout the remainder of the interior of said housing.

3. A dish and silverware washing, rinsing, and 60 drying machine comprising a housing having a shallow trough in the bottom wall thereof, rotatable means including a plurality of axially spaced blades arranged to dip into said trough for impelling fluid from said trough at a high velocity 65 and in a finely atomized condition throughout a portion of the interior of said housing extending from the discharge side of the trough, fixed deflector elements extending transversely of the trough between adjacent blades to cooperate with the 70 rotatable means for directing fluid from the trough at a high velocity and in a finely atomized condition throughout the remainder of the interior of said housing, and means for supporting objects in both of the said portions of the housing 75

with the surfaces of the objects which are to be treated positioned at an angle to the direction of travel of the fluid.

4. A dish and silverware washing, rinsing and drying machine comprising a housing having a shallow trough in the bottom wall thereof, rotatable means for impelling fluid from said trough at a high velocity and in a finely atomized condition throughout a portion of the interior of said housing extending from the discharge side of the trough, means cooperating with the rotatable means for directing fluid from the trough at a high velocity and in a finely atomized condition throughout the remainder of the interior of said housing, and a rack for supporting objects in both of the said portions of the housing with the surfaces of the objects which are to be treated positioned at an angle to the direction of travel of the fluid, said rack comprising a series of dish troughs extending longitudinally of the portion of the housing supplied with fluid by said rotatable means and arranged at such an angle to the perpendicular as to cause the fluid from said rotatable means to treat all surfaces of dishes arranged on said troughs, a series of bowl shelves extending longitudinally of the portion of the housing supplied with fluid by said cooperating means and arranged at such an angle to the perpendicular as to cause the fluid from said cooperating means to treat all surfaces of bowls arranged on said shelves, and glass and cup shelves extending longitudinally of the upper central portion of the housing and arranged at such angles to the perpendicular as to cause the fluid impelled by the rotatable means and the cooperating means to treat all surfaces of glasses and cups arranged on said shelves.
5. A dish and silverware washing, rinsing and drying machine comprising a housing having a shallow trough in the bottom wall thereof, an impeller shaft journaled in the housing above said trough, a series of axially spaced impeller wheels having longitudinally curved blades fixed to said shaft, the blades being of proper length to dip into said trough, a fixed deflector blade extending transversely of the trough between each adjacent pair of impeller wheels and terminating in an upwardly curved end portion at the discharge side of the impeller wheels, an upstanding longitudinally extending flange positioned at the edge of the discharge side of the trough and terminating short of both end walls of the housing, said flange restricting return flow of fluid from the portion of the bottom of the housing located on the discharge side of the trough to the opposite end regions of the trough, said fixed deflector blades being in part supported on and held in proper spaced relation by said flange, means for supplying the housing with a treatment fluid to a level below the impeller shaft, and means for rotating said impeller wheels at high speed to cause fluid from the bottom of the housing to be expelled at high velocity and in a finely atomized condition from the ends of the impeller blades and the upwardly curved ends of the deflector blades.
6. A dish and silverware washing, rinsing and drying machine comprising a housing having a shallow trough in the bottom wall thereof, an impeller shaft journaled in the housing above said trough, a series of axially spaced impeller wheels having longitudinally curved blades fixed to said shaft, the blades being of proper length to dip into said trough, a fixed deflector blade extending transversely of the trough between each adjacent pair of impeller wheels and terminating in an upwardly curved end portion at the discharge side of the impeller wheels, means for supplying the housing with a treatment fluid to a level below the impeller shaft, and means for rotating said impeller wheels at high speed to cause fluid from the bottom of the housing to be expelled at high velocity and in a finely atomized condition from the ends of the impeller blades and the upwardly curved ends of the deflector blades.

each adjacent pair of impeller wheels and terminating in an upwardly curved end portion at the discharge side of the impeller wheels, said housing to be supplied with a treatment fluid to a level below the impeller shaft while the impeller is inoperative, and means for rotating said impeller wheels at high speed to cause fluid from the bottom of the housing to be expelled at high velocity and in a finely atomized condition from the ends of the impeller blades and the upwardly curved ends of the deflector blades.

7. A dish and silverware washing, rinsing and drying machine comprising a housing having a shallow trough in the bottom wall thereof, an upstanding flange on the bottom wall of the housing shaped and arranged as a continuation of one side of the trough, an impeller shaft journaled in the housing above said trough, a series of axially spaced impeller wheels having longitudinally curved blades fixed to said shaft, the blades being of proper length to dip into said trough, a fixed deflector blade extending transversely of the trough between each adjacent pair of impeller wheels and terminating in an upwardly curved end portion at the discharge side of the impeller wheels, means for supplying the housing with a treatment fluid to a level below the impeller shaft, and means for rotating said impeller wheels at high speed to cause fluid from the bottom of the housing to be expelled at high velocity and in a finely atomized condition from the ends of the impeller blades and the upwardly curved ends of the deflector blades.

8. A dish and silverware washing, rinsing and drying machine comprising a housing having a shallow trough in the bottom wall thereof, an upstanding flange on the bottom wall of the housing shaped and arranged as a continuation of one side of the trough and being of less length than and centrally arranged with respect to said trough to provide fluid return openings to the trough, an impeller shaft journaled in the housing above said trough, a series of axially spaced impeller wheels having longitudinally curved blades fixed to said shaft, the blades being of proper length to dip into said trough, a fixed deflector blade extending transversely of the trough between each adjacent pair of impeller wheels and terminating in an upwardly curved end portion at the discharge side of the impeller wheels, means for supplying the housing with a treatment fluid to a level below the impeller shaft, and means for rotating said impeller wheels at high speed to cause the fluid from the bottom of the housing to be expelled at high velocity and in a finely atomized condition from the ends of the impeller blades and the upwardly curved ends of the deflector blades.

9. A dish and silverware washing, rinsing and drying machine comprising a housing having a shallow trough in the bottom wall thereof, an impeller shaft journaled in the housing above said trough, a series of axially spaced impeller wheels having longitudinally curved blades fixed to said shaft, the blades being of proper length to dip into said trough, a fixed deflector blade extending transversely of the trough between each adjacent pair of impeller wheels and terminating in an upwardly curved end portion at the discharge side of the impeller wheels, means for supplying the housing with a treatment fluid to a level below the impeller shaft, and means for rotating said impeller wheels at high speed to cause fluid from the bottom of the housing to be expelled at high velocity and in a finely atomized condition from the ends of the impeller blades and the upwardly curved ends of the deflector blades.

condition from the ends of the impeller blades and the upwardly curved ends of the deflector blades, and means associated with the side of the trough where the impeller blades withdraw from the same constructed and arranged to prevent return flow of fluid into the trough in a manner to interfere with the dispersion of fluid by said blades.

10. A dish and silverware washing, rinsing and drying machine comprising a housing having a shallow trough in the bottom wall thereof, an impeller shaft journaled in the housing above and in an eccentric relation with respect to said trough, a series of axially spaced impeller wheels 15 having longitudinally curved blades fixed on said shaft, the blades being of proper length to dip into said trough, a series of fixed deflector blades extending transversely of the trough in an elevated relation with respect to the bottom of the 20 trough and being located one between each adjacent pair of impeller wheels, said deflector blades terminating in upwardly curved end portions located above the axis of rotation of the impeller shaft and with the direction of curvature determining the direction of discharge of 25 treatment fluid from said blades, and means for

rotating the impeller shaft at a high speed to cause the impeller blades to project treatment fluid at high velocity and in a finely atomized condition from the ends of the impeller blades and fixed deflector blades.

5

11. A dish and silverware washing, rinsing and drying machine comprising a housing having a shallow trough in the bottom wall thereof, a plurality of axially spaced rotatable impellers arranged to dip fluid from the trough for impelling it at a high velocity and in a finely atomized condition through slightly more than one-half of the interior of said housing including the discharge side of the trough, and stationary deflector blades positioned to lie between adjacent 15 impellers and receiving fluid from the trough which is set in motion by the action of the impellers, said deflector blades being shaped and supported in a manner to extend through the trough and upwardly therefrom to direct the 20 fluid received by the blades at a high velocity and in a finely atomized condition to the portion of the housing not receiving fluid directly from the impellers.
